ABSTRACT OF THE DISCLOSURE

A plastic member is rubbed upon a water-soaked silicon carbide sandpaper to form a solution of water, plastic pigment and abrasive. Plastic members of various configurations are placed upon the sandpaper and solution in a preselected pattern and upon drying, the solution beads up around the plastic members allowing a drying effect in the configurations of the plastic members. Paint pigment of various colors may be added to the solution depending upon the intensity desired of particular colors. The solution and pigment then are spread in varied intensities by various tools and the illustration is permitted to dry.

BRIEF SUMMARY AND OBJECTS OF THE INVENTION

The present invention relates to art forms and more particularly to the method of forming a picture or illustration utilizing plastic in conjunction with emery cloth or emery paper.

In a preferred procedure, a colloidal suspension of liquid, plastic, and emery abrasive is provided on the emery paper. Design begins with the placing of plastic of preselected configurations upon the solution and upon drying, the solution beads up around the plastic resulting in a drying effect in the shape of the plastic used. Color pigments may be added to enhance the design. As the illustration dries, the solution will become more opaque. If desired, an acrylic fixer may be applied for better adhesion of the plastic to the emery paper.

One of the primary objects of the invention is the provision of a method whereby a free art form can be imposed on emery paper.

Another object of the invention is the provision of a method of using plastics and emery paper as a medium of expression.

Other objects and advantages of the invention will become apparent when considered in view of the following detailed description.

BRIEF DESCRIPTION OF THE FIGURES

FIG. 1 is a top plan view of waterproof emery paper used as the background of the illustration;

FIG. 2 is a perspective view of the emery paper having a liquid applied thereto and illustrating a plastic member being scraped against the emery paper in a circular motion to work up a colloidal suspension of liquid, plastic pigment and emery abrasive;

FIG. 3 is a perspective view of the emery paper with plastic of various shapes being placed upon the solution and paper;

FIG. 4 is a perspective view of the emery paper after at least a partial drying of the solution and removal of the plastic shapes and after color pigments have been applied to the selected areas of the emery paper; and

FIG. 5 is a perspective view of the emery paper after excess solution has been applied to the desired areas and a tool is used to mix, swirl or draw the desired effect on the emery paper.

DETAILED DESCRIPTION OF THE INVENTION

Referring to the drawing, an illustration or picture may be produced by utilizing the various method steps disclosed by FIGS. 1-5. In FIG. 1, there is shown a waterproof silicon carbide paper 10 of the desired size and shape which is used as the background of the art form or illustration to be composed. The sandpaper 10, hereinafter referred to as emery paper, should have a suitable grit which allows the abrasive of the paper to protrude through the film of plastic pigment and yet which does not overpower the film of plastic which results in obliteration of the design and effect. One suitable type of paper is a 220 grit silicon carbide paper. The emery paper 10 gives maximum contrast by utilizing its reflective qualities.

In FIG. 2, the emery paper 10 has been soaked with a non-acrylic fluid, preferably water, before the plastic pigment is produced. The plastic pigment is produced by scraping a plastic member 14 over the water-soaked emery paper 10. The scraping or grinding of the plastic member 14 on the wet emery paper 10 results in a colloidal suspension 12 of water, plastic pigment and emery abrasive.

Designing of the illustration or picture is initiated by the placement of plastic in various shapes 16 on the surface of the emery paper 10 and in contact with the solution 12. The solution beads up around the various plastic shapes 16 which allows a drying effect of the plastic pigment 18 in configurations which conform generally to the surfaces of the various plastic members in contact with the emery paper 10. While the plastic member 16 illustrated in FIG. 3 have a cylindrical or rounded surface which contacts the emery paper, it is to be understood that the plastic may be of various configurations such as straight or arcuate segments, etc., and that the number and sizes of the plastic members 16 may vary.

In some instances, paint pigments may be used in conjunction with but not in place of the plastic pigments to enhance the basic design effect. Also paint pigments may be used depending upon the intensity desired of particular colors or color contrasts. One or more colors of paint pigment in solution may be applied to the emery paper by syringes or other suitable means. As shown by FIG. 4, a paint pigment 20 of a first color is applied to selected areas of the emery paper 10. Excess solution 12 may also be applied to the emery paper. Plastic tools may be used to spread the paint pigment and excess solution in varied intensities which produces lines, shadings, etc.

Alternatively, a paint pigment 22 of a color in addition to paint pigment 20 may be applied to the emery paper along with excess solution 12. The pigment 22 is applied in selected areas which permeates the previous design relative to the amount used. Afterwards, tools may be used to further mix or swirl the paint pigments 20 and 22 and excess solution 12 to obtain the desired effect. An enhancement of depth perception can be achieved in this manner.

The illustration or picture then must be allowed to dry. Upon drying, the solution 12 becomes more opaque and white. For better adhesion of the plastic to the emery paper 10, an acrylic fixer may be applied. Alternatively, the illustration or picture may be covered with a sheet of plastic to prevent flaking of the plastic pigment and paint pigment. The picture then may be matted and framed.

I claim:

1. The method of forming an illustration comprising the steps of providing a sheet of sandpaper of a selected size and configuration, applying water to the abrasive surface of the sandpaper, forming a solution of water, plastic pigment and abrasive on the surface of the sandpaper

by rubbing a plastic member upon the wet abrasive surfaces of the sandpaper, positioning at least one plastic member having a preselected configuration upon the solution and sandpaper, beading up portions of the solution around the plastic member having a preselected configuration by at least partially drying the solution, removing the plastic member, and spreading the solution in a selected pattern and manner to provide the desired effect upon the sandpaper.

2. The method of forming an illustration as recited in claim 1, wherein the water is applied to a waterproof, silicon carbide sandpaper.

3. The method of forming an illustration as recited in claim 1, and further including the step of applying an acrylic fixer to the illustration upon drying of the solution.

4. The method of forming an illustration as recited in claim 1, and further including the step of applying paint pigment to the sandpaper before the step of spreading of the solution in a selected pattern to enhance the basic design effect.

5. The method of forming an illustration as recited in claim 4, wherein paint pigments of various colors are applied to the sandpaper before the solution is spread in a selected pattern.

6. The method of forming an illustration as recited in claim 5, including the step of applying an acrylic fixer to the illustration.

7. The method of forming an illustration as recited in claim 1, wherein a plurality of plastic members of preselected configurations are arranged upon the sandpaper and the solution beads up around the plurality of plastic members upon drying of the solution.

8. The method of forming an illustration as recited in claim 7, and further including the steps of applying paint pigments of various colors to the solution and sandpaper before the solution is spread in a selected pattern, the water being applied to soak the abrasive surface of a silicon carbide sandpaper.
